UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

MECHANISM FOR FORMING HINGES OF LASTS FOR SHOES.

Application filed June 6, 1923. Serial No. 643,609.

My invention relates to a mechanism for forming the hinges of lasts for shoes.

It is the object of my invention to provide a process and mechanism for forming the hinge portions of a wooden last, which lasts are used for the purpose of manufacturing shoes.

It will be understood that such hinges must be formed with great accuracy by severing the last body at predetermined angles and curves. It is also essential that the severing of the last into two parts and the removal of the surplus material be accomplished without injury to the last body.

It is a further object of my invention to provide a mechanism which will accurately effect these severing operations of my process.

It is a further object to provide such a mechanism which will duplicate the same operations in the same way repeatedly, so that there will be uniformity in the product resulting from the practice of my process and the use of my mechanism.

Referring to the drawings:

Figure 1 is an elevation of a last before being worked upon by my process and mechanism.

Figure 2 is an elevation of the last after the first step in the process has been taken, and a V-shaped plug or section has been removed, to permit of the last collapsing after the hinge has been formed.

Figure 3 is an elevation showing the second step of the process, in which the semi-circular hinge has been cut in the last.

Figure 4 is a side elevation of the last at the completion of the process, after the bottom portion of the last has been severed, thus forming the last in two separate parts.

Figure 5 is a plan view of the mechanism for removing the V-shaped plug or section from the last.

Figure 6 is an elevation on the side away from the operator of the mechanism shown at Figure 5.

Figure 7 is an enlarged side elevation of the last support.

Figure 8 is a plan view of the mechanism for forming the hinge of the last.

Figure 9 is a plan view of the mechanism for severing the two portions of the last from one another after the hinge is formed.

Figure 10 is an enlarged detail plan of the mechanism shown in Figure 8, showing the mechanism in two positions, at the start and at the end of the hinging operation.

Figure 11 is a section through the support or block upon which is pivoted the carrier illustrated in the plan view in Figure 10.

Figure 12 is a side elevation of Figure 8.

In my invention, the first step in the process is to sever the V-shaped section from the upper portion of the last; the second step is the hinging operation to form the hinge between the two sections of the last; and the last step of the process is the severing operation to sever the two portions of the last from one another.

It will be understood that before the process has started upon the last, it has received its preliminary shape and has had drilled in it, by any desired means, two holes parallel to one another, one hole being located in one half of the last, and the other hole in the other half. These holes are used for the positioning pins to be hereinafter described.

With this general statement of the process, the following is a detailed description of the drawings:

The last shown in Figure 1 consists of a toe portion and a heel portion, respectively designated 1 and 2. In the toe portion is the transverse hole 3, and in the heel portion the transverse opening 4.

As will be hereinafter described, the saw makes a cut along the line 5 to form the rear face of the toe portion, and then along the line 6 to form the face of the heel portion. The block therebetween is thus removed. It usually leaves a ridge at the base of the V-shaped cut as at 7, which is dressed away by the saw by a slight finishing operation.

The semi-circular hinge is then formed on the line 8, as will be hereinafter de-

scribed. The complete severing of the two parts of the last is accomplished by the saw passing along the line 9.

In order to accomplish the first step of the process of forming a hinge last, I provide the mechanism shown in Figures 5, 6, and 7. Broadly this mechanism consists of a holder which may be moved to varying positions to carry the last with it, so that the saw will effect cuts in the last body in different parts thereof. The second feature of the machine is the means for moving this carrier to and from the operator for effecting the transverse cut in the last body. The third feature of the machine is the lateral movement of the saw for the different positioning of the saw relative to the last body, at the will of the operator.

It will be observed in this machine that it is unnecessary, unless desired, to demount the last body from its holder during the several cuts which are taken through the last body. It is also possible to adjust the last body upon its holder at a position away from the saw, thus lending a considerable factor of safety to the operation of the machine.

As to the details of the machine:

It is mounted upon standards 10. These standards carry a cross member or guide 11, upon which is mounted the saw carriage or support 12. This saw carriage slides laterally, due to the operation thereon of a shifting lever 13, which is pivoted thereto at 14. This shifting lever is connected to a second lever 15, which projects adjacent to the operator, so that the operator's hand or knee may move this lever, and thus shift the saw laterally of the machine.

The saw 16 of circular type is mounted on a saw shaft 17 in the bearings 18 and 19, which are carried on the top of the carriage 12. A pulley 20 is mounted on this shaft 17, and a belt 21 is in turn mounted upon the pulley. This belt is driven from any suitable source of power, such as from the pulley 22, which is mounted on a conventional shaft, which in turn carries the pulley 23 fixed thereon, and a loose pulley 24, which alternately engage with the main driving belt 25. These details are not of the essence of this invention in any way.

The movement of the carriage and the saw to the left hand is resisted by the helical spring 26, which is seated at 27 in the side of the carriage 12 at one end, and at its other end is seated in the standard 10 in a pocket 28. The position of this spring in the pocket is determined by the set-screw 29 and the lock-nut 30.

The limits of movement of the saw in either direction are fixed by the set-screws 31 and 32 carried by the standards on either side of the carriage. Mounted on these

standards, or upon a portion of them, is a vertically moving support moving in a guide way. The vertical member of this support is designated 33, and has a dovetailed portion 34 sliding in a dovetailed groove in one of the standards, on the exterior thereof, as at 35. A threaded eye 36 carried by the vertical member 33 engages with a worm 37, which is actuated by a hand wheel 38, so that the elevation of this portion of the mechanism may be adjusted.

Mounted upon this vertical member 33 is a plate 39, retained thereon by a bolt 40. This plate, which runs transversely of the machine from a point adjacent the saw to a point adjacent the operator, is provided with a dovetailed groove 41, in which a dovetailed member 42 travels. The dovetailed member 42 forms the base or carrier for the last holder. This carrier is designated 43, and projects upwardly and laterally from the saw in an arch-shaped neck 44, upon which is mounted pivotally the holding-plate 45. It is upon this holding plate that are located the two retaining pins 46 and 47 upon which the last is mounted. These pins project into the holes 4 and 3 in the last. The plate itself is mounted upon the shaft 48, which rotates in the collar 49 of the bracket 44.

It will be noted that this supporting plate 45 has a cut-away portion partially circular, as at 50, for accommodating the saw as it enters the last. The block itself is moved about its pivot by the arm or lever 51, which is held by the hand of the operator. It may be rested against the pin 52 or against the pin 53, depending upon the position of the last.

The last is mounted upon these pins upside down, so that in the position shown in Figure 6 the saw is in position for forming the forward or toe face 5 of the cut which removes the V-shaped segment or section from the last. The movement upwardly of the handle 51 would position the last for taking the cut from the heel portion.

These pins 53 and 52 are mounted on a backplate 54, and are adjustable by wing-nuts 55 in a groove 56 on that plate. They also project through a groove 57 in a forward plate 58. The lock-nut and bolt 59 serve to hold the two plates together. The plate 54 is mounted at 60 upon the bracket 43 of the carriage. This permits an adjustment of the position of these pins or stops 52 and 53, which determine the position of the holding plate.

A further adjustment of the last-supporting pin 47 is effected by a lock-nut 61, which holds the pin in any desired position in the slot 62 in the holding plate 45.

The carrier 43 may be moved to or from the operator, as will be seen in Figure 5, by the operator grasping the handle 63. The support 44 may be shifted laterally upon its

carrier block by loosening the nut 64 on the bolt 65, which is carried by the carrier block. A slot 66 in the bracket 44 accommodates this adjustment.

5 It is therefore possible to move the last to and from the operator or laterally of the operator. It is possible to adjust the extent of the rotation of the last on the holding plate, and it is also possible to adjust the 10 position of one pin on the holding plate to the other. It is possible to vary the position of the saw laterally.

With these several adjustments all within the ready reach of the operator, I have provided a machine for this step of the process which is readily adjustable to varying conditions, sizes, and dimensions. It is also possible to vary the entire elevation of the last-supporting structure by the worm 37 and 20 the hand wheel 38.

The mechanism to effect the second step of the process, namely, the hinge-forming step, is as follows:

I provide a table 67, upon which there is 25 mounted a plate 68. This plate carries an adjustable stop 69. The stop has a slot 70 for the reception of the adjusting bolt 71 carried by the plate 68. A nut 72 fixes the stop 69 in any predetermined position. This 30 stop is used for limiting the movement of the carrying plate 73, as will be further described hereinafter. This carrying plate 73 is pivoted upon the supporting plate by a pivot 74. 74 is adjacent to and connected 35 with a projecting finger 75. A semi-circular cut-away portion or recess, known as a saw-slot, is formed in the plate 73 as at 76, adjacent to the finger 75. One part of this plate carries the pin 77, and the other part of the plate carries the pin 78, which is adjustable in the carrying plate 73 in the slot 79. Located adjacent to this saw-slot in this carrying plate is a vertically moving bandsaw 80. The last is mounted upon the pins 40 with the saw substantially parallel to and closely adjacent to the base 7 of the cut-away portion in the top of the last which resulted from the previous step in the process. The last and holding plate 73 can then be moved 45 about the pivot, thus forming the semi-circular hinge, by the saw cutting away the wood along the hinge line as at 8 in Figure 3.

A supplementary positioning arrangement 50 is provided in having the plate 68, which is a relatively heavy plate, pivotally mounted upon the table 67 by means of the link 81, which is pivoted at 82 to the table 67, and is connected at 83 to the plate 68. It is positioned by the stop 84.

60 By this arrangement, it is possible to mount the last on the carrying block with the plate 68 away from the saw, and then to bring the entire mechanism bodily adjacent to the saw, after which time the carry-

ing plate is rotated for effecting the cut by 65 the saw. This enables the operator to mount the last and adjust it, with respect to the carrying plate 73 and the plate 68, without being in proximity to the saw.

It will also be observed that the table 67 70 is provided with a saw-slot 86.

Turning to the mechanism for effecting the last step in the process of severing the halves in the last, it will be observed that a 75 table 67 is provided, having a saw-slot 86 in which is located a saw 80. A block 88 is pivotally mounted on the table 67 by a link 89, which is connected to the table at 90, and to the block at 91.

This block 88 has at its outer end a cut-away portion substantially V-shaped as at 92 to accommodate the saw. Mounted upon the block adjacent to this cut-away portion, is a carrying plate 93, having the pin 94, which projects into a hole in one half of 85 the last, the hole of the other half of the last adapted to receive a pin 94^a mounted on the block 88. This plate 93 is adjustable on the block 88 through a bolt 95 carried by the block which works in a slot 96 in the plate 93. A nut 97 serves to locate the plate 93 on the block 88 at predetermined 90 positions. The block itself is limited in its position on the table 67 by the stop 98. By 95 moving the block and the last mounted thereon against the saw 80, the slightly circular cut 9 is taken, to sever the two halves of the last from one another.

Thus I am enabled to form from a single 100 block by my process and mechanism, a hinged last.

It will be understood that I desire to comprehend within my invention suitable modifications necessary to adapt it to varying conditions, and fairly comprehended 105 within the claims herein.

Having thus fully described my invention, what I claim as new, and desire to secure by Letters Patent, is:

1. In a last-hinging machine, a frame, a transversely moving saw support mounted on said frame, means for moving said support on said frame having its actuating end adjacent an operator, a last carrier, a support therefor mounted on said frame, means for moving said carrier to and from said saw, a holding plate pivotally mounted on said carrier adjacent said saw, said plate having a cut-away portion for the reception 110 of the saw as the plate is moved with the last thereon, means on the holding plate for supporting said last on either side of the portion being cut.

2. In a last-hinging machine, a frame, a transversely moving saw support mounted on said frame, means for moving said support on said frame having its actuating end 125

adjacent an operator, a last carrier, a support therefor mounted on said frame, means for moving said carrier to and from said saw, a holding plate pivotally mounted on said carrier adjacent said saw, said plate having a cut-away portion for the reception of the saw as the plate is moved with the last thereon; means on the holding plate for supporting said last on either side of the portion being cut, and means for moving the holding plate to regulate the cut in the last.

3. In a last-hinging machine, a frame, a transversely moving saw support mounted on said frame, means for moving said support on said frame having its actuating end adjacent an operator, a last carrier, a support therefor mounted on said frame, means for moving said carrier to and from said saw, a holding plate pivotally mounted on said carrier adjacent said saw, said plate having a cut-away portion for the reception of the saw as the plate is moved with the last thereon, means on the holding plate for supporting said last on either side of the portion being cut, means for moving the holding plate to regulate the cut in the last, means for limiting the movement of said regulating means, and means for fixing the elevation of the carrier and holding plate with respect to said saw.

holding plate to regulate the cut in the last, and means for limiting the movement of said regulating means.

4. In a last-hinging machine, a frame, a transversely moving saw support mounted on said frame, means for moving said support on said frame having its actuating end adjacent an operator, a last carrier, a support therefor mounted on said frame, means for moving said carrier to and from said saw, a holding plate pivotally mounted on said carrier adjacent said saw, said plate having a cut-away portion for the reception of the saw as the plate is moved with the last thereon, means on the holding plate for supporting said last on either side of the portion being cut, means for moving the holding plate to regulate the cut in the last, means for limiting the movement of said regulating means, and means for fixing the elevation of the carrier and holding plate with respect to said saw.

In testimony whereof, I affix my signature.

GEORGE CLAUSING.
